SHOE SEWING MACHINE

Edward Quinn, Malden, and Alfred R. Morrill,
Beverly, Mass.

Application April 7, 1938, Serial No. 200,644

33 Claims. (Cl. 112—62)

The present invention relates to shoe sewing machines, and more particularly to machines adapted for sewing the upper to the sole of a shoe unsupported on a last.

5 The invention is herein disclosed as embodied in a straight needle over arm sewing machine of the general type having stitch forming devices which include a work piercing awl and a straight needle movable to feed the work, and devices arranged for guiding and for supporting the work in position to cause the needle to enter and emerge from the same side of the work, which include a work support adapted to enter a stitch receiving channel formed in the sole, a presser foot to bear against the upper at the edge of the sole, an upper guard, and a horn arranged to extend within the shoe and bear against the inner surface of the sole at the sewing point.

10 The illustrated machine is similar in many respects to that illustrated in the patent to Edward Quinn No. 2,142,966, dated January 3, 1939, and is similarly adapted for operation upon turn shoes or slippers in which the upper has been temporarily attached to the sole for inserting a row of 15 stitches through the upper and between-substance between a shoulder adjacent the sole edge and a stitch receiving channel formed on the same side of the work.

15 While the several features of applicant's invention are particularly adapted for use with, and constitute an improvement upon the machine of, the Quinn patent above referred to, it will be understood that certain features of the invention are equally applicable to machines having a different construction and arrangement of the 20 stitch forming and work supporting and guiding devices, and to machines adapted for performing a stitching operation upon shoes in which the upper has not previously been attached to the edge 25 of the sole.

25 It is a principal object of the present invention to provide in a machine of the general type described, in which the needle is arranged to enter and to emerge from the same side of the work, a 30 novel and improved arrangement of the work supporting and guiding devices to provide a more adequate support of the shoe at the sewing point to insure the proper location and formation of the stitches in the sewing of a seam, particularly 35 in operating upon shoes in which inferior grade or light weight stock is employed.

35 It is another object of the invention to provide in a machine of the general description having a horn arranged to extend within the shoe and to 40 bear against the inner surface of the sole adjacent

the edge thereof at the sewing point, a novel and improved construction and arrangement of the horn actuating mechanism to insure the proper positioning of the work during the stitch forming cycle, and to maintain a substantial guiding control of the shoe during the work feed.

45 It is another object of the invention to provide a novel and improved upper guard, and actuating mechanism therefor, which is well adapted for use in a machine of the general type described to insure the proper positioning of the portions of the upper and lining adjacent to and in advance of the sewing point during the progress of the stitching operation about the shoe.

50 It is a further object of the invention to provide a novel and improved timing in the operation of the work supporting and guiding devices during each stitch forming and work feeding cycle of the machine to properly position and support the shoe for the operation of the stitch forming devices.

55 With these and other objects in view as may hereinafter appear, certain features of the invention relate to improvements in the construction and mode of operation of the actuating mechanism for the horn whereby the horn is yieldingly engaged against the inner surface of the sole and is locked in this work engaging position to provide a positive lateral support of the shoe by the horn against the thrust of the presser foot, awl and needle, and is thereafter moved a predetermined small distance away from its work engaging position, the extent of this relieving action being gauged to maintain a substantial guiding relation of the horn with the shoe during the work feed.

60 Other features of the invention relate to the provision in a machine of the type described for stitching together the soles and previously attached uppers of light weight turn shoes and slippers while unsupported on a last, of an improved upper guard which is lifted a small amount from the work during each feeding cycle of the machine, and of which the work engaging surfaces are constructed and arranged to position the upper and lining from the sole edge prior to the engagement of the presser foot, and to clear loose portions of the lining in advance of the stitching without placing any excessive strain on the engaged portions of the work which might 65 tend to break down or to distort the sole edge and attached upper from their proper stitch receiving positions.

70 Other features of the invention relate to improvements in construction and organization of

the actuating mechanisms for the shoe supporting and guiding devices to secure a more efficient cooperation of these parts to properly support and to guide the shoe during the progress of 5 the stitching operation about the margin of the sole.

The several features of applicants' invention consist also in the devices, combinations and arrangement of parts hereinafter described and 10 claimed which, together with the advantages to be obtained thereby will be readily understood by one skilled in the art from the following description taken in connection with the accompanying drawings in which:

15 Figure 1 is a view in left side elevation, partly in section, of a straight needle sewing machine embodying in a preferred form the several features of applicants' invention, only so much of the machine being illustrated as believed necessary to illustrate the connection of the present invention therewith; Figure 2 is a sectional view, looking from the rear, taken on the line 2--2 of Figure 1; Figure 3 is a detail view of certain of the parts shown in Figure 2, illustrating more 20 particularly the channel engaging work supports and applicants' improved upper guard; Figure 4 is a view in front elevation of substantially the parts shown in Figure 1, but with a portion of the sewing head broken away to show underlying 25 parts; Figure 5 is a sectional plan view taken on the line 5--5 of Figure 4; Figure 6 is a sectional view taken on the line 6--6 of Figure 5; Figure 7 is a detail sectional view of the presser-foot lock mechanism illustrated in Figure 6, but 30 for a different position of the parts; Figure 8 is a detail sectional view in left side elevation, taken on the line 8--8 of Figure 6; and Figure 9 is an enlarged detail view in left side elevation of certain of the parts shown in Figure 1, illustrating 35 more particularly the positions of the horn and upper guard during the work feed.

The machine disclosed in the drawings as embodying in a preferred form the several features of the present invention, is a wax thread chain 40 stitch machine of the overarm type having a work support comprised by two relatively movable channel engaging members 20 and 22, and a straight hook needle 24 located beneath the work, and a cooperating presser foot 26, awl 28 and looper 30 located in the overarm generally indicated at 32 above the work. The needle is mounted on a swinging support 34 for movements in the line of feed to impart a positive step-by-step feeding movement of the work. The present 45 machine is particularly constructed and arranged for sewing a line of stitches around the margin of a turn shoe or slipper, which is preferably assembled in a reverse position with the upper and lining attached thereto, cemented or otherwise temporarily secured to a shoulder formed in any edge portion of the sole. The shoe or slipper is placed in the machine with the sole in a sharply inclined position, so that the needle at its work piercing stroke will enter the stitch 50 receiving channel in the shoe sole, and passing through the between substance, will emerge through the upper and lining in the groove formed by the shouldered edge of the shoe sole. The work is supported vertically against the 55 downward thrust of the awl 28 and against the work piercing and loop drawing strokes of the needle 24 between the work supports 20 and 22 engaging within the stitch receiving channel, and the presser foot 26 which engages the upper or lining as the case may be in the groove or hollow 60

edge portion of the shoe sole. In order to assist in positioning the shoe, a stationary guard plate 38 is mounted beneath the work for engagement with the shoe sole, and is adjustable to determine accurately the angle at which the needle and awl pass through the work. The machine is also provided with a shoe supporting horn 40 arranged to extend within the shoe and bear against the inner surface of the sole at the sewing point and an upper guard member 42 which 10 is movable in a vertical plane into and out of engagement with the shoe to correctly position the upper or upper and lining in advance of the operation of the presser foot and stitch forming devices during the progress of the sewing operation about the margin of the shoe. The construction and arrangement of the shoe supporting and feeding devices is such as to permit of a fully automatic operation of the machine to transfer the point of operation about the shoe without the 15 necessity of assistance or attention on the part of the operator.

The stitch forming and work feeding devices of the machine including specifically the needle, awl, looper and presser foot, are constructed and 20 arranged to have the usual timing of these parts, and are actuated from driving connections which have been more fully set forth in the patent to Edward Quinn above referred to, and are well known in the art. Inasmuch as these connections form no part of the present invention, only sufficient disclosure of the same has been made to indicate the general arrangement of the same in the machine. As best shown in Figs. 2 and 4, the needle 24 is mounted on the upper end of 25 the needle bar 46 to reciprocate within the swinging bracket 34, and is actuated from a forwardly extending rock shaft 48 in the base 50 through lever 52 and connecting link 54. The awl is driven from a forwardly extending rotating shaft 56 mounted in the overarm 32, reciprocatory movement being imparted to the awl by means of a link 58 connected at one end to the awl bar 60 and at its upper end to an eccentric pin carried on the forward end of the rotating 30 shaft 56.

The presser foot 26 of the present machine, is rigidly secured to the lower end of a vertically movable presser foot bar 62 held yieldingly in engagement with the work by means of a leaf 55 spring 64 (see Figs. 1 and 2) which engages against the upper end of the presser foot bar. The presser foot bar is positively lifted to permit the feeding of the work through connections which include a forwardly extending rock shaft 55 supported in the overarm 32, and provided at its forward end with a presser foot lifting lever 68. The rocking movement of the lever 68 is rendered operative to lift the presser foot through a self-adjusting locking device which includes a loose nut 70 screw-threaded to the presser foot bar, a sleeve member 72 loosely supported on the bar and arranged to engage upon both sides of the nut 70, and a clamping lever 74 supported by the sleeve member 72, when the clamping lever 74 is engaged by the presser foot lifting lever 68 to clamp the nut 70 in locking engagement with the presser foot bar 62, and thereafter to raise the presser foot 26 out of engagement with the work. Inasmuch as the presser foot actuating mechanism as thus far described, is substantially that illustrated in the patent to Merrick No. 629,108, July 18, 1899, no further description or illustration thereof is believed necessary.

The construction and operation of the presser foot actuating mechanism, is generally speaking similar to that described and illustrated in the patent to Edward Quinn above referred to, a 5 relatively light spring 64 being employed to move the presser foot into clamping engagement with the work, this spring operating in connection with a presser foot locking device to secure a firm support of the work during the back feed 10 and upward thrust movements of the needle, without at the same time causing the shoe to become impaled upon the tips of the work supporting members 20 and 22 extending into the stitch receiving channel with resultant injury to the 15 work or the machine parts during the work feed.

In carrying out the present invention, an improved presser foot locking device has been devised which cooperates in a new and more efficient manner to provide a firm support for the work, and at the same time to permit the work to be lifted slightly prior to the beginning of the feed movement of the needle, so that the work may be freed from engagement with the channel supports 20 and 22. To this end applicants provide a locking pawl and ratchet type lock for locking the presser foot in engagement with the work in combination with connections which are directly controlled by movement of the presser foot lifting lever 68, and may be very accurately timed to release the presser foot lock slightly in advance of the lifting of the presser foot, and also before the needle has reached the limit of its up stroke whereby the work is permitted to move upwardly with the needle slightly away from the channel work supports 20 and 22. With this construction and arrangement of the presser foot lock, a tight clamping engagement of the presser foot can be maintained to provide a firm and accurate support of the work as the needle follows the awl upwardly through the work, the work then being released only as the needle nears the limit of its upward movement.

Applicants' improved presser foot lock comprises a slide 80 secured at its lower end to a pin 82 mounted in a bracket 84 which is rigidly secured to move with the presser foot bar 62 (see Fig. 2). The slide 80 is provided with a series of ratchet teeth 86 which are adapted to be engaged by a locking pawl 88 mounted to turn on a stationary pin 90 carried on the overarm 32 of the machine. A small compression spring 92 seated in a recess 94 is arranged for engagement with the pawl 88 to maintain the pawl in locking engagement with the ratchet teeth 86. The operation of the pawl 88 is controlled from the presser foot lifting lever 68 through connections which include a laterally extending arm 96 secured to turn with the pawl 88, and having at its outer end an adjustable stop screw 98 adapted for engagement with an abutment 100 carried on the hub of the presser foot lifting lever 68. As the presser foot lever 68 begins to move upwardly in a counterclockwise direction, from the position shown in Fig. 4 to the presser foot lift position shown in Fig. 6, the abutment 100 contacting with the stop screw 98 acts immediately to move the pawl 88 out of engagement with the ratchet teeth 86 so that the presser foot 26 and presser foot bar 62 are free to move upwardly 60 with the work against the relatively light pressure of spring 64, as the needle completes its upward movement. Continued movement of the presser foot lifting lever 68 to the position of Fig. 6 now causes the lever to engage with the clamping lever 74 to lift this presser foot from the

work. When the presser foot lifting lever 68 is again moved to its low position to permit the return of the presser foot against the work, the pawl 88 is permitted to move under the pressure of its spring 92 into locking engagement with the ratchet teeth 86.

In order to permit the release of the presser foot lock and the lifting of the presser foot 26 by the actuation of the usual treadle actuated lever of these machines, generally indicated at 102, a 10 pawl release lever 104 is loosely supported on the supporting pin 82 for movement into and out of engagement with the pawl 88. At its lower end the pawl release lever 104 is provided with an inclined surface 106 which is arranged to be engaged by a laterally extending arm 108 formed in the forward end of the treadle actuated presser foot lifting lever 102. The actuation of the foot treadle (not shown) causes the treadle actuated presser foot lifting lever 102 to move upwardly, 15 engaging the surface 106 to move the release lever 104 in a counterclockwise direction as shown in Fig. 4, to release the pawl 88, and thereafter to raise the presser foot bar 62 and presser foot 26 out of engagement with the work. 20

The horn 40 of applicants' improved machine, comprises a U-shaped member which is pivotally mounted to move bodily toward and away from its work engaging position in a direction inclined downwardly and forwardly from the sewing point, and is further supported to swing freely about a horizontal axis approximately normal to the surface of the shoe sole in the machine, and passing through the sewing point. The horn 40 is loosely supported on a pivot pin 110 carried on a horn supporting lever 112 which is in turn loosely mounted on a stationary pivot pin 114 on the overarm 32. In order to provide for adjustments of the horn 40 with relation to the sewing point, the pivot pin 110 is supported for vertical adjustment in a slot 116 formed in a bracket 118 forming part of the lever 112. The bracket 118 is slidably mounted for adjustment in the line of feed in the lever 112, being clamped in adjusted position by means of a 30 set screw 120.

The actuating connections for the horn 40 comprise a vertically movable control bar 122 which is slidably supported in a casing 124 attached to the forward end of the overarm 32, 50 and is connected at its lower end to the horn lever 112 by means of a link 126. The control bar 122 is moved yieldingly in a downward direction to engage the horn 40 against the work by means of a compression spring 128 which is supported within a cylindrical chamber 130 formed in the casing 124, and at its lower end engages against a forwardly extending lug 132 adjacent the lower end of the control bar 122. An adjustable stop screw 134 screw-threaded into 60 the upper end of the chamber 130, and arranged to engage against the upper end of the spring 128, provides a convenient means for adjusting the pressure exerted by the spring 128.

In accordance with one feature of the present 65 invention the actuating connections above described, including the spring actuated control bar 122, link 126, and horn supporting lever 112 are constructed and arranged to secure a substantially irreversible action to lock the horn 70 40 in work engaging position. To this end the supporting pins 136 and 137 for the link 126 mounted respectively on the control bar 122 and on the lever 112 are so arranged that downward movement of the horn control bar 122 75

will cause the link 126 to approach a substantially straight line position with relation to the direction of thrust of the horn 40 about its pivot 114 away from the work, this position, as best shown in Fig. 1, being at a sharp angle to the direction of movement of the control bar 122 under the pressure of its spring 128. With this construction and arrangement of the actuating connections, it will readily be seen that a powerful toggle action is provided to assist the spring 128 in moving the horn against the work, the two arms of the toggle comprising the link 126 pivotally supported on the control bar 122 and the horn supporting lever 112 movable about the fixed pivot 114, these connections then acting as above pointed out, to provide a locking action to prevent movement of the horn in the reverse direction away from the work.

In accordance with another feature of the invention, a novel and improved mechanism is provided actuated from the usual awl motion of the machine, for relieving the pressure of the horn upon the work during the work feed, this mechanism being constructed and arranged to move the horn a small predetermined distance from its work engaging position, which is sufficient only to free the work, while at the same time maintaining a substantial guiding relation of the horn with the shoe during the feed.

While in the Quinn patent above referred to, it was proposed to maintain a proper position of the shoe for the operation of the stitching devices through the engagement of the presser foot with the grooved edge of the shoe sole, difficulty has been encountered during operation upon shoes constructed of light weight or inferior stock in securing an adequate cooperation between the presser foot and the grooved edge of the shoe sole to insure the proper positioning of the work for the formation of successive stitches. Applicants' improved arrangement of the horn mechanism in which the horn is moved a uniform small distance from its engaging position regardless of variations in work thickness, has the particular advantage that the horn may be positioned sufficiently close to the inner edge of the shoe sole during the work feed, to provide a substantial lateral guiding support for the shoe which will insure a proper positioning of the presser foot with relation to the sole edge, and a correct location of the successive stitches of the seam.

Further in accordance with the present invention, the actuating connections for the horn are constructed and arranged to provide an improved timing of the relieving and engaging movements of the horn with relation to the cyclic operation of the cooperating machine parts, and more particularly the presser foot. In applicants' improved construction, the horn is moved away from the work prior to the starting of the work feed, and preferably slightly in advance of the lifting of the presser foot, and is again engaged with the work before the presser foot. This timing of the horn motion to cause the horn to engage against and support the inner edge of the sole at the sewing point prior to the re-engagement of the presser foot with the work, has the specific advantage of preventing lateral displacement of the sole edge due to the action of the presser foot, which might otherwise result when shoes constructed of light weight or inferior stock are being operated upon.

In the illustrated construction, the relieving and engaging movements are imparted to the

horn through connections which are actuated from the awl bar 60, and are particularly arranged to secure the predetermined small movement of the horn from the work engaging position and the desired timing of said relieving and engaging movements with relation to the advancing and retracting stroke of the awl bar. The mechanism for lifting the horn comprises a nipping block 140 which is loosely mounted on the horn control bar 122, and is normally forced downwardly by means of two compression springs 142 and 144 engaging the opposite sides thereof, against a stationary supporting surface 146 formed in the casing 124. The actuating connections for the nipping block include a lever 152 arm 148 which is formed on a rock shaft 150, and is arranged to engage against the rear side of the nipping block 140. A second lever arm 152 adjustably secured to the rock shaft 150, is arranged to be engaged by an actuating block 154 20 adjustably secured to the awl bar 60, these parts being so arranged that the block 154 during the upward movement of the awl bar 60 will engage with a cammed face of the lever arm 152, and rock the shaft 150 and lever arm 148 through 25 a predetermined angle, thus causing the nipping block 140 to be tipped into gripping engagement with and to lift the horn control bar 122 a predetermined small amount. The connections above described including the nipping block 140 30 for relieving the horn engaging pressure upon the work, are constructed and arranged to cause the horn to be disengaged from the work at the desired point in the up-stroke of the awl bar 60, and to permit the re-engagement of the horn with 35 the work also at the desired point in the down-stroke of the awl bar 60, the timing of these parts being such as to cause the horn to engage against and support the inner edge of the sole at the sewing point prior to the re-engagement of 40 the presser foot with the work.

In accordance with another feature of the invention, applicants' machine is provided with a novel and improved upper guard 42, as best shown in Figs. 3 and 9 of the drawings. The upper guard is formed on the lower end of a slide member 156 which is movable in a vertical plane in a guideway 160 into and out of engagement with the work. The work engaging portion of the upper guard 42 comprises a flat plate, which is sloped downwardly and rearwardly at an angle, the rear face thereof providing a broad upper engaging surface, the lower edge 164 of the upper guard 42 being arranged to bear against the upper to the rear of the presser foot, and extending in the direction of feed a substantial distance in advance of the sewing point. That portion of the edge 164 which is opposite the sewing point, is provided with a slight recess 166, as best shown in Fig. 3, to provide adequate clearance for the needle. There is also provided on the leading side of the upper guard 42, a flanged portion 168 which extends transversely across the line of feed, and is further provided with a downwardly projecting tip 170 which extends downwardly over the shouldered edge of the sole and attached upper. The length and shape of the depending portion 170 is such as to cause this part to overlie the edge of the sole even when in the retracted work feeding position of Fig. 9. The flanged portion 168 including the tip 170 serves the particular purpose of clearing the loose portions of the lining in advance of the sewing point to prevent possible injury to the 75

lining from the operation of the stitch forming devices.

Applicants' improved upper guard is particularly adapted for use in operating upon light weight shoes and slippers in which the upper or upper and lining have been previously cemented or otherwise attached to the edge of the shoe sole. During the operation upon shoes of this type, the upper guard operates in a most efficient manner to properly position the upper and lining away from the sole edge to permit an unobstructed operation of the presser foot and sewing devices, without at the same time causing any undue lateral strains to be placed on the work which might result in tearing the upper loose from the sole edge or in a lateral placement or breaking down of the sole edge.

In the preferred construction shown, the upper guard 42 is arranged to be moved vertically a predetermined small distance away from the work during each feeding operation of the shoe. The timing of the upper guard, horn and presser foot motions is such as to cause the upper guard to engage against the work in advance of the horn 40 and presser foot 26, and to cause the upper guard to be disengaged from the work only after both the horn and the presser foot have started their retracting movements. The upper guard 42 is moved yieldingly into engagement with the work by means of a torsion spring 172 which is supported at one end on a pin 174 on the horn actuating bar 122, and at its other end engages against the upper end on the slide support 156 for the upper guard 42. A predetermined upward movement of the upper guard 42 is obtained during a portion of each stitch forming and work feeding cycle of the machine, by means of an actuating lever 176 loosely supported to turn on the stationary pivot 114. A small tension spring 178 secured at one end to a pin 180 on the hub of the lever 176, and at its other end to a pin 182 on the horn supporting lever 112, tends to swing the actuating lever 176 downwardly in a counterclockwise direction, as shown in Fig. 1, to a limiting position determined by engagement of the lever with an adjustable stop pin 184. Movement of the actuating lever 176 in a reverse or clockwise direction, as shown in Fig. 9, causes the cammed upper surface 186 thereof to engage against a bearing surface formed by the upper end of a slot 188 within which the actuating lever 176 extends to raise the upper guard 42 out of engagement with the work.

The actuating lever 176 is moved in a clockwise direction to raise the upper guard 42 from the work, by means of a nib 189 formed on a collar 190 on the awl bar 60. During the upward movement of the awl bar the nib 189 engages against a cammed surface 192 formed in the forward edge of the actuating lever 176 to move the lever to its raised position, the lever then being supported in this position by continued movement of the nib 189 onto a flattened surface 194 of the lever 176. It will readily be seen that these connections operate to move the lever 176 and the upper guard 42 controlled thereby to a predetermined raised position during each upward stroke of the awl bar 60.

In order that the treadle actuated presser foot lifting lever 102 may be rendered operative also to retract the horn 40 and upper guard 42 to free the work from the machine, the lateral extension 108 of the lever 102 above described, is arranged upon lifting the lever 102 to engage beneath a

lug 196 secured to the horn control bar 122 to raise the bar against the pressure of the spring 128. At the same time a lug 200 formed on the lower end of the horn control bar 122 engages beneath an offset upper end 202 of the slide support 156 for the upper guard 42, thus raising the upper guard away from the work. 5

It will be understood that the invention is not limited to the specific embodiment shown, and that various deviations may be made therefrom without departing from the spirit and scope of the appended claims.

What is claimed is:

1. A machine for sewing the upper to the sole of a shoe while unsupported on a last having, in combination, stitch forming and work feeding devices including a needle, devices arranged to support the work in position to cause the needle to enter and emerge from the same side of the work comprising a work support to enter a stitch receiving channel, a presser foot to bear against the upper at the edge of the sole, a horn arranged to extend within the shoe and bear against the inner surface of the sole at the sewing point, and means for actuating the horn to retract the horn from its work engaging position to a position with relation to the surface of the work at which the engaging pressure upon the sole is relieved, and at which a substantial guiding relation is maintained between the work and the horn 30 during the work feed. 25

2. A machine for sewing the upper to the sole of a shoe while unsupported on a last having, in combination, stitch forming and work feeding devices including a needle, devices arranged to support the work directly against the thrust and withdrawing stroke of the needle in position to cause the needle to enter and emerge from the same side of the work, a horn extending within the shoe arranged to bear against the inner surface of the sole adjacent the edge thereof at the sewing point, and thereby to cooperate with the work supporting devices to position the shoe laterally in the path of needle movement, and means for actuating the horn to retract the horn a predetermined uniform distance from the surface of the work regardless of work thickness, said distance being gauged to maintain a substantial guiding relation between the horn and the work during the work feed. 35 40 45 50 55

3. A machine for sewing the upper to the sole of a shoe while unsupported on a last having, in combination, stitch forming devices including a needle, devices arranged to support the work in position to cause the needle to enter and emerge from the same side of the work comprising a work support to enter a stitch receiving channel, a presser foot to bear against the upper at the edge of the sole, a horn arranged to extend within the shoe and bear against the inner surface of the sole at the sewing point, and means for yieldingly engaging the horn against the work, and for locking the horn in work engaging position. 60 65

4. A machine for sewing the upper to the sole of a shoe while unsupported on a last having, in combination, stitch forming and work feeding devices including a needle, devices arranged to support the work in position to cause the needle to enter and emerge from the same side of the work comprising a work support to enter a stitch receiving channel, a presser foot to bear against the upper at the edge of the sole, a horn arranged to extend within the shoe and bear against the inner surface of the sole at the sewing point, means for yieldingly engaging the horn against 70 75

the work and for locking the horn in work engaging position, and means to relieve the pressure of the horn on the sole during a portion of each stitch forming and work feeding cycle of the machine.

5. A machine for sewing the upper to the sole of a shoe while unsupported on a last having, in combination, stitch forming and work feeding devices including a needle, devices arranged to support the work directly against the thrust and withdrawing stroke of the needle in position to cause the needle to enter and emerge from the same side of the work comprising a work support to enter a stitch receiving channel, a presser foot to bear against the upper at the edge of the sole, a work supporting and guiding element arranged to bear against the inner surface of the sole at the sewing point, and means for actuating said work supporting and guiding element to engage said element against the shoe sole and to retract said element a predetermined uniform distance from said engaging position regardless of the thickness of the work, said distance being gauged to maintain a substantial guiding relation between the work supporting and guiding element and the work during the work feed.

6. A machine for sewing the upper to the sole of a shoe while unsupported on a last having, in combination, stitch forming and work feeding devices including a needle, devices arranged to support the work directly against the thrust and withdrawing stroke of the needle in position to cause the needle to enter and emerge from the same side of the work, a horn extending within the shoe arranged to bear against the inner surface of the sole adjacent the edge thereof at the sewing point, and thereby to cooperate with the work supporting devices to position the shoe laterally in the path of needle movement, and means for actuating the horn to engage the horn against the shoe sole and to retract the horn a predetermined uniform distance from said engaging position regardless of the thickness of the work to relieve the pressure of the horn on the sole during each stitch forming and work feeding cycle of the machine.

7. A machine for sewing the upper to the sole of a shoe while unsupported on a last having, in combination, stitch forming and work feeding devices including a needle, devices arranged to support the work in position to cause the needle to enter and emerge from the same side of the work comprising a work support to enter a stitch receiving channel in the sole, a presser foot to bear against the upper at the edge of the sole, a horn arranged to extend within the shoe and bear against the inner surface of the sole at the sewing point, and means for actuating the horn to engage the horn against the sole and to retract the horn a predetermined uniform distance from the shoe engaging position regardless of work thickness to relieve the pressure of the horn on the shoe during portions of each stitch forming and work feeding cycle of the machine.

8. A machine for sewing the upper to the sole of a shoe while unsupported on a last having, in combination, stitch forming and work feeding devices including a needle, devices arranged to support the work directly against the thrust and withdrawing stroke of the needle in a position to cause the needle to enter and emerge from the same side of the work, a horn extending within the shoe arranged to bear against the inner surface of the sole adjacent the edge thereof at the sewing point, and thereby to position the

shoe laterally in the path of needle movement, means for actuating the horn including means for yieldingly moving the horn against the shoe sole, and means for retracting the horn a predetermined uniform distance from the shoe engaging position regardless of work thickness to relieve the pressure of the horn on the sole during a portion of each stitch forming and work feeding cycle of the machine.

9. A machine for sewing the upper to the sole of a shoe while unsupported on a last having, in combination, stitch forming devices including a needle, devices arranged to support the work directly against the thrust and withdrawing stroke of the needle in a position to cause the needle to enter and emerge from the same side of the work, a horn extending within the shoe arranged to bear against the inner surface of the sole adjacent the edge thereof at the sewing point, and thereby to cooperate with the work supporting devices to position the shoe laterally in the path of needle movement, and means for actuating the horn including means for yieldingly engaging the horn against the work, an actuating member having a predetermined throw, and a connection actuated thereby to operatively connect the horn to said actuating member to move the horn a predetermined uniform distance from the work engaging position regardless of the thickness of the work.

10. A machine for sewing the upper to the sole of a shoe while unsupported on a last having, in combination, stitch forming and work feeding devices including a needle, devices arranged to support the work directly against the thrust and withdrawing stroke of the needle in a position to cause the needle to enter and emerge from the same side of the work, a horn extending within the shoe arranged to bear against the inner surface of the sole adjacent the edge thereof at the sewing point, and thereby to cooperate with the work supporting devices to position the shoe laterally in the path of needle movement, means for yieldingly engaging the horn against the work including a connection having a substantially irreversible action to lock the horn against the work, and means acting on said connection to relieve the pressure of the horn on the sole during a portion of each stitch forming and work feeding cycle of the machine.

11. A machine for sewing the upper to the sole of a shoe while unsupported on a last having, in combination, stitch forming and work feeding devices including a needle, devices arranged to support the work directly against the thrust and withdrawing stroke of the needle in a position to cause the needle to enter and emerge from the same side of the work, a horn extending within the shoe arranged to bear against the inner surface of the sole adjacent the edge thereof at the sewing point, and thereby to cooperate with the work supporting devices to position the shoe laterally in the path of needle movement, means for yieldingly engaging the horn against the work including a connection having a substantially irreversible action to lock the horn against the work, and means acting on said connection to move the horn away from the work a predetermined amount during a portion of each stitch forming and work feeding cycle of the machine.

12. In a machine for sewing the upper to the sole of a shoe while unsupported on a last having, in combination, stitch forming and work feeding devices including a needle, devices arranged to

- support the work in position to cause the needle to enter and emerge from the same side of the work comprising a work support to enter a stitch receiving channel formed in the sole, a presser foot to bear against the upper at the edge of the sole, a horn extending within the shoe to bear against the inner surface of the sole at the sewing point and thereby to position the sole edge laterally in the path of needle movement, means for actuating the presser foot and horn to release the work during the work feed, and thereafter to clamp the work, said actuating means including means acting to move the horn into clamping position prior to the engagement 10 of the presser foot with the work.
13. In a machine for sewing the upper to the sole of a shoe while unsupported on a last having, in combination, stitch forming and work feeding devices including a needle, devices arranged to support the work in position to cause the needle to enter and emerge from the same side of the work comprising a work support to enter a stitch receiving channel formed in the sole, a presser foot to bear against the upper at the edge of the sole, a horn arranged to extend within the shoe and bear against the inner surface of the sole at the sewing point, means for actuating the presser foot to engage and disengage the presser foot 20 from the work during portions of each stitch forming and work feeding cycle of the machine, means for actuating the horn including means for yieldingly engaging the horn against the work, and means for retracting the horn a predetermined uniform distance from the work including a nipping block, a horn actuating lever arranged to engage therewith, and connections actuated by the awl motion for rocking said lever through a predetermined angle to retract the horn, and thereafter to re-engage the horn with the work.
14. A machine for sewing the upper to the sole of a shoe while unsupported on a last having, in combination, stitch forming and work feeding devices including an awl having a work piercing and retracting movement, a needle, devices arranged to support the work in position to cause the needle to enter and emerge from the same 25 side of the work comprising a work support to enter a stitch receiving channel formed in the sole, a presser foot to bear against the upper at the edge of the sole, a horn extending within the shoe to bear against the inner surface of the sole at the sewing point and thereby to position the sole edge laterally in the path of needle movement, means for actuating the presser foot 30 to release the work during work feed, means for actuating the horn including means for moving the horn yieldingly against the work and for locking the horn in work engaging position, and means to relieve the pressure of the horn upon the work during the work feed operable to re-engage the horn with the work prior to the engagement of the presser foot.
15. A machine for sewing the upper to the sole of a shoe while unsupported on a last having, in combination, stitch forming and work feeding devices including an awl having a work piercing and retracting movement, a needle, devices arranged to support the work in position to cause the needle to enter and emerge from the same 35 side of the work comprising a work support to enter a stitch receiving channel formed in the sole, a presser foot to bear against the upper at the edge of the sole, a horn extending within the shoe to bear against the inner surface of the sole at the sewing point and thereby to position the sole edge laterally in the path of needle movement, means for actuating the presser foot to release the work during work feed, and means actuated by the retracting movement of the awl 40 to move the horn a predetermined uniform distance from the work regardless of work thickness, and actuated by the work piercing movement of the awl to re-engage the horn with the work prior to the engagement of the presser foot.
16. A machine for sewing the upper to the sole of a shoe while unsupported on a last having, in combination, stitch forming and work feeding devices including a needle, devices arranged to support the work in position to cause the needle to enter and emerge from the same side of the work comprising a work support to enter a stitch receiving channel formed in the sole, a presser foot to bear against the upper at the edge of the sole, a horn arranged to extend within the shoe and bear against the inner surface of the sole at the sewing point, means for actuating the presser foot to engage and disengage the presser foot 45 from the work during portions of each stitch forming and work feeding cycle of the machine, means for actuating the horn including means for yieldingly engaging the horn against the work, and means for retracting the horn a predetermined angle to retract the horn, and thereafter to re-engage the horn with the work.
17. In a machine for sewing the upper to the sole of a turn shoe having a stitch receiving channel formed in the sole, and having the upper temporarily secured to the sole, the combination of stitch forming and work feeding devices including a needle, devices arranged to support the work in position to cause the needle to enter and emerge from the same side of the work comprising a work support to enter the stitch receiving 50 channel, a presser foot to bear against the upper at the edge of the sole, means for lifting the presser foot to release the work during the work feed, and an upper guard movable in a direction substantially normal to the sole edge toward and away from the work surface, and having work engaging surfaces arranged to force the upper against and loose portions thereof away from the point of attachment with the sole edge, and means for actuating the upper guard to release 55 the work during work feed, adapted to re-engage the upper guard with the work prior to movement of the presser foot into clamping engagement with the upper.
18. In a machine for sewing the upper to the sole of a turn shoe having a stitch receiving channel formed in the sole, and having the upper temporarily secured to the sole, the combination of stitch forming and work feeding devices including a needle, devices arranged to support the work in position to cause the needle to enter and emerge from the same side of the work comprising a work support to enter the stitch receiving channel, a presser foot to bear against the upper at the edge of the sole, means for lifting the presser foot during a portion of each stitch forming and work feeding cycle, an upper guard movable toward and away from the work surface, and having work engaging surfaces constructed and arranged to force the upper against and loose portions thereof away from the point of attachment at the sole edge, and means for actuating the upper guard to release the work during the work feed adapted to re-engage the upper guard with the work prior to movement of the presser 60
19. In a machine for sewing the upper to the sole of a turn shoe having a stitch receiving channel formed in the sole, and having the upper temporarily secured to the sole, the combination of stitch forming and work feeding devices including a needle, devices arranged to support the work in position to cause the needle to enter and emerge from the same side of the work comprising a work support to enter a stitch receiving channel formed in the sole, a presser foot to bear against the upper at the edge of the sole, a horn arranged to extend within the shoe and bear against the inner surface of the sole at the sewing point, means for actuating the presser foot to engage and disengage the presser foot from the work during portions of each 65 stitch forming and work feeding cycle of the machine, means for actuating the horn including means for yieldingly engaging the horn against the work, and means for retracting the horn a predetermined angle to retract the horn, and thereafter to re-engage the horn with the work.
20. In a machine for sewing the upper to the sole of a turn shoe having a stitch receiving channel formed in the sole, and having the upper temporarily secured to the sole, the combination of stitch forming and work feeding devices including a needle, devices arranged to support the work in position to cause the needle to enter and emerge from the same side of the work comprising a work support to enter a stitch receiving channel formed in the sole, a presser foot to bear against the upper at the edge of the sole, a horn arranged to extend within the shoe and bear against the inner surface of the sole at the sewing point, means for actuating the presser foot to engage and disengage the presser foot from the work during portions of each 70 stitch forming and work feeding cycle of the machine, means for actuating the horn including means for yieldingly engaging the horn against the work, and means for retracting the horn a predetermined angle to retract the horn, and thereafter to re-engage the horn with the work.
21. In a machine for sewing the upper to the sole of a turn shoe having a stitch receiving channel formed in the sole, and having the upper temporarily secured to the sole, the combination of stitch forming and work feeding devices including a needle, devices arranged to support the work in position to cause the needle to enter and emerge from the same side of the work comprising a work support to enter a stitch receiving channel formed in the sole, a presser foot to bear against the upper at the edge of the sole, a horn arranged to extend within the shoe and bear against the inner surface of the sole at the sewing point, means for actuating the presser foot to engage and disengage the presser foot from the work during portions of each 75 stitch forming and work feeding cycle of the machine, means for actuating the horn including means for yieldingly engaging the horn against the work, and means for retracting the horn a predetermined angle to retract the horn, and thereafter to re-engage the horn with the work.

foot into clamping engagement with the upper.

19. In a machine for sewing the upper to the sole of a turn shoe having a stitch receiving channel formed in the sole, the combination of stitch forming and work feeding devices including an awl having a work-piercing and retracting movement, a needle movable to feed the work, devices arranged to support the work in position to cause the needle to enter and emerge from the same side of the work comprising a work support to enter the stitch receiving channel, a presser foot to bear against the upper at the edge of the sole, means for lifting the presser foot to release the work during the work feed, an upper guard movable into and out of engagement with the shoe and having work engaging surfaces constructed and arranged to position the upper with relation to the sole edge, and means rendered operative by the retracting movement of the awl to move the upper guard away from the work.

20. In a machine for sewing the upper to the sole of a turn shoe having a stitch receiving channel formed in the sole, the combination of stitch forming and work feeding devices including an awl having a work-piercing and retracting movement, a needle movable to feed the work, devices arranged to support the work in position to cause the needle to enter and emerge from the same side of the work comprising a work support to enter the stitch receiving channel, a presser foot to bear against the upper at the edge of the sole, means for lifting the presser foot to release the work during the work feed, an upper guard movable into and out of engagement with the shoe and having work engaging surfaces constructed and arranged to position the upper with relation to the sole edge, and means comprising cam and follower elements associated respectively with the upper guard and with the awl for raising the upper guard to a predetermined position during the retracting movement of the awl.

21. In a machine for sewing the upper to the sole of a turn shoe having a stitch receiving channel formed in the sole, the combination of stitch forming and work feeding devices including a needle, devices arranged to support the work in position to cause the needle to enter and emerge from the same side of the work comprising a work support to enter the stitch receiving channel, a presser foot to bear against the upper at the edge of the sole, an upper guard movable in a single path into and out of engagement with the shoe, and having work engaging surfaces constructed and arranged to position the upper with relation to the sole edge, a horn arranged to extend within the shoe and bear laterally against the inner surface of the sole at the sewing point, and means for actuating each of the upper guard presser foot and horn to release the work during the work feed, and to re-engage the upper guard and horn with the work prior to the engagement of the presser foot.

22. In a machine for sewing the upper to the sole of a turn shoe having a stitch receiving channel formed in the sole and having the upper temporarily secured to the sole, the combination of stitch forming and work feeding devices including a needle, devices arranged to support the work in position to cause the needle to enter and emerge from the same side of the work comprising a work support to enter the stitch receiving channel formed in the sole, and a presser foot to bear against the upper at the edge of the sole, means for lifting the presser foot during a portion of each stitch forming and work feeding

cycle, an upper guard having a work engaging surface arranged to bear against the upper on that side of the sewing point away from the sole edge, and extending in advance of the sewing point in the line of feed, an upper engaging surface extending upwardly and laterally for engagement with adjacent portions of the upper, and means for imparting a reciprocatory movement to the guard in a single path into and out of engagement with the shoe whereby said surfaces operate to force the upper against and loose portions thereof away from the sole edge prior to movement of the presser foot into clamping engagement with the upper.

23. In a machine for sewing the upper to the sole of a turn shoe having a stitch receiving channel formed in the sole, and having the upper temporarily secured to the sole, the combination of stitch forming and work feeding devices including a needle, devices arranged to support the work in position to cause the needle to enter and emerge from the same side of the work comprising a work support to enter the stitch receiving channel formed in the sole, and a presser foot to bear against the upper at the edge of the sole, means for lifting the presser foot during a portion of each stitch forming and work feeding cycle, an upper guard having a work engaging surface arranged to bear against the upper on that side of the sewing point away from the sole edge and extending in advance of the sewing point, a second work engaging surface extending transversely across the line of feed in advance of the sewing point and including a depending portion arranged to extend downwardly over the sole edge, and a third upper engaging surface extending upwardly and laterally from the sewing point into engagement with adjacent portions of the upper, and means for reciprocating the guard in a single path toward and away from the sewing point to force the upper against and loose portions thereof away from the sole edge prior to movement of the presser foot into clamping engagement with the upper.

24. A machine for sewing the upper to the sole of a shoe in which the sole is formed with a stitch receiving channel, having in combination, stitch forming and work feeding devices including a needle movable to feed the work, devices arranged to support the work in position to cause the needle to enter the stitch receiving channel and to emerge from the same side of the work, comprising a work support to enter the stitch receiving channel, a presser foot arranged to bear against the upper at the edge of the sole, means for pressing the presser foot yieldingly against the work, a presser foot locking device, a presser foot lifting device, and means operative to release the locking device as the needle approaches the limit of its work piercing stroke and prior to the lifting of the presser foot whereby the work is caused to move slightly away from the work support under the influence of the work piercing thrust of the needle against the presser foot and said yielding presser foot pressing means prior to the feeding of the work.

25. A machine for sewing the upper to the sole of a shoe in which the sole is formed with a stitch receiving channel, having in combination, stitch forming and work feeding devices including a needle movable to feed the work, devices arranged to support the work in position to cause the needle to enter the stitch receiving channel and to emerge from the same side of the work,

- comprising a work support to enter the stitch receiving channel, a presser foot arranged to bear against the upper at the edge of the sole, means for pressing the presser foot yielding against the work, a presser foot locking device comprising a ratchet and locking pawl cooperating therewith, a presser foot lifting lever, a connection controlled by the movement of said lever to disengage the pawl from the ratchet, said connection having means for adjustment to cause the locking device to be released as the needle approaches the limit of its work piercing stroke and prior to the lifting of the presser foot by the lever, whereby the work is caused to move slightly away from the work support under the influence of the work piercing thrust of the needle against the presser foot and said yielding presser foot pressing means prior to the feeding of the work.
26. A machine for sewing the upper to the sole of a shoe in which the sole is formed with a stitch receiving channel, having in combination, stitch forming and work feeding devices including a needle movable to feed the work, devices arranged to support the work in position to cause the needle to enter the stitch receiving channel and to emerge from the same side of the work, comprising a work support to enter the stitch receiving channel, a presser foot arranged to bear against the upper at the edge of the sole, means for pressing the presser foot yielding against the work, a presser foot locking device comprising a ratchet and locking pawl cooperating therewith, a presser foot lifting lever, a connection actuated by movement of the lifting lever to disengage the pawl, a manually operable presser foot lifting lever, and a throw-out lever rendered operative by movement of the manually operable presser foot lifting lever to disconnect the locking pawl from the ratchet.
27. In a machine for sewing the upper to the sole of a turn shoe having a stitch receiving channel formed in the sole, the combination of stitch forming and work feeding devices including a needle, devices arranged to support the work directly against the thrust and withdrawing stroke of the needle in a position to cause the needle to enter and emerge from the same side of the work including a work support to enter the stitch receiving channel, a presser foot movable toward and away from the shoe and arranged to bear against the upper at the edge of the sole, an upper guard movable toward and away from the shoe, and having work engaging surfaces constructed and arranged to position the upper with relation to the sole edge, and means for actuating each of the upper guard and the presser foot to release the work during the work feed, and to re-engage the upper guard with the work prior to the engagement of the presser foot.
28. In a machine for sewing the upper to the sole of a turn shoe having a stitch receiving channel formed in the sole, the combination of stitch forming and work feeding devices including a needle, devices arranged to support the work directly against the thrust and withdrawing stroke of the needle in a position to cause the needle to enter and emerge from the same side of the work comprising a work support to enter the stitch receiving channel formed in the sole, a presser foot movable toward and away from the shoe and arranged to bear against the upper at the edge of the sole, an upper guard movable toward and away from the shoe in a direction substantially normal to the sole edge, and having work engaging surfaces constructed and arranged to engage the upper against the sole edge, and to position adjacent portions thereof away from the sole edge, and means for actuating each of the presser foot and upper guard to release the work during the work feed, and to re-engage the upper guard with the work prior to the engagement of the presser foot.
29. In a machine for sewing the upper to the sole of a turn shoe having a stitch receiving channel formed in the sole, and having the upper temporarily secured to the sole edge, the combination of stitch forming and work feeding devices including a needle, devices arranged to support the work directly against the thrust and withdrawing stroke of the needle in a position to cause the needle to enter and emerge from the same side of the work comprising a work support to enter the stitch receiving channel formed in the sole, a presser foot movable toward and away from the shoe and arranged to bear against the upper at the edge of the sole, an upper guard movable toward and away from the shoe, said upper guard having a work engaging surface arranged to bear against the upper at that side of the sewing point away from the sole edge and extending in advance of the sewing point, and a depending portion arranged to extend downwardly over the sole edge in advance of the sewing point to clear loose portions of stock during the work feed, and means for actuating each of the presser foot and upper guard to release the work during the work feed and to re-engage the upper guard with the work prior to the engagement of the presser foot.
30. In a machine for sewing the upper to the sole of a turn shoe having a stitch receiving channel formed in the sole, the combination of stitch forming and work feeding devices including a needle, devices arranged to support the work in position to cause the needle to enter and emerge from the same side of the work comprising a work support to enter the stitch receiving channel, a presser foot movable toward and away from the work and arranged to bear against the upper at the edge of the sole, an upper guard movable toward and away from the work and having work engaging surfaces constructed and arranged to position the upper with relation to the sole edge, a horn arranged to extend within the shoe and bear laterally against the inner edge of the sole at the sewing point, and means for actuating each of the upper guard, the presser foot and horn to release the work during the work feed.
31. A shoe sewing machine having, in combination, stitch forming and work feeding devices including a work support, a presser foot, and a work piercing element arranged to enter the side of the work opposite from the presser foot, actuating means for the presser foot including means for moving the presser foot yielding against the work and for raising the pressure foot to permit the feeding of the work, a presser foot lock operable to lock the presser foot against the work, and means operable as said work piercing element approaches the limit of its work piercing stroke and prior to the raising of the presser foot for the work feed to permit a slight upward movement of the work under the influence of the work piercing thrust of said element against the yielding resistance of the presser foot.

foot and said yielding presser foot pressing means prior to the work feed.

32. A shoe sewing machine having, in combination, stitch forming and work feeding devices including a work support, a presser foot movable toward and away from the work, a needle arranged to enter the side of the work opposite from the presser foot and to feed the work, actuating means for the presser foot including means for moving the presser foot yieldingly against the work, a presser foot locking device, a presser foot lifting device for raising the presser foot to permit the feeding of the work, and means for unlocking the presser foot as the needle approaches the limit of its work piercing stroke and prior to the lifting of the presser foot, whereby the work is caused to move slightly away from the work support under the influence of the work piercing thrust of the needle against the presser foot and said yielding

presser foot pressing means prior to the work feed.

33. A shoe sewing machine having, in combination, stitch forming and work feeding devices including a hook needle, a work support, a presser foot movable toward and away from the work, and actuating means for the presser foot including spring means urging the presser foot against the work, means for raising the presser foot to permit the feeding of the work, means for locking the presser foot in the spring-seated position against the work, and means acting to relieve said locking action in that portion of the work piercing stroke of the needle after the needle has entered the work to permit the presser foot to be yieldably supported against the work during a portion of the stitch forming cycle prior to the lifting of the presser foot.

EDWARD QUINN.
ALFRED R. MORRILL. 20
